PROPELLER

Abraham Edison Greene, Carmanville,
Newfoundland

Application August 31, 1938, Serial No. 227,861

2 Claims. (Cl. 170—159)

This present invention relates to certain new and useful improvements in a propeller.

The primary object of the invention resides in the provision of a propeller of generally improved and simplified construction and increased efficiency.

The invention has for another object the provision of a propeller of the character stated which is constructed so as to operate against the water and force the same rearwardly so as to obtain the highest efficiency of operation of the propeller and the maximum forward movement of the propeller and the boat operated thereby, with the minimum strain on the propeller.

15 The invention has for a further object the provision of a propeller of the character stated by means of which a boat may be propelled at the maximum speed or stopped in the minimum period of time, with the maximum strain on the propeller at all times.

20 The invention has for a still further object the provision of a propeller of the character stated which is of simple and inexpensive construction as well as increased efficiency and may be readily manufactured at small cost and installed on the propeller shaft of boats of various types and may be retailed at a popular price with good profit, thus providing a commercially attractive proposition.

25 To the accomplishment of these and related objects as shall become apparent as the description proceeds, my invention resides in the construction, combination and arrangement of parts as shall be hereinafter more fully described, illustrated in the 30 accompanying drawing, and pointed out in the claims hereunto appended.

35 The invention will be best understood and can be more clearly described when reference is had to the drawing, forming a part of this disclosure, 40 wherein like characters indicate like parts throughout the several views.

In the drawing—

Figure 1 is a front elevation of the improved propeller; and

45 Figure 2 is a side elevation, at right angles to Figure 1.

50 Referring more in detail to the drawing, it is to be noted that the propeller includes a sleeve 6 of elongated form and having a longitudinal slot 7 therein, whereby the propeller sleeve 6 may be readily keyed to the propeller shaft of a boat or the like. A pair of forward reversely extended arcuate propeller blades 8 project radially from diametrically opposite portions of the propeller sleeve 6, near the forward end of the latter, said

5 sleeve 6 thus serving as a hub. The blades 8 on issuing from the sleeve 6 swing through about 180° in a free wing, increasing in width from their inner attached ends to their outer ends with their free extremities 9 cut straight across and the corners 10 thereof rounded. The blades 8 are not curved transversely, having relatively flat forward and rear faces, always in a plane at right angles to the axis of said sleeve but move rearwardly gradually from their inner fixed ends to their 10 free outer ends 9, the two blades 8 describing an arc oppositely directed from the sleeve or hub 6 so as to follow one another during rotation of the propeller. A second, similar pair of propeller blades 11 have their narrow inner ends extended 15 from diametrically opposite points on the propeller sleeve or hub 6, near the rear end of the latter and at right angles to the points of connection of the first mentioned blades 8 with said sleeve or hub 6. This second pair of propeller blades 11 also on 20 issuing from the sleeve 6 swing through approximately 180° and increase in width from their attached inner ends to their free outer or rear ends 12 which are cut straight across with the corners 13 thereof rounded and likewise; this second pair of blades 11 are gradually bent rearwardly 25 from their fixed inner ends to their free outer ends 12, although the blades 11 are not curved transversely. The two blades 11 describe arcs similar to those described by the blades 8 with each blade 30 11 extended oppositely from the other so that they will follow one another in the water, during operation of the propeller. By this construction and arrangement of the blades 8 and 11, which are of relatively thin material, on the sleeve or hub 6, 35 each of the pairs of blades 8 and 11, together with the sleeve or hub 6 appear to describe the letter S when looking at one end of the propeller sleeve or hub 6 with the two S's arranged at right angles with one in front of and overlapping the other; 40 the individual blades 8 and 11 of each of the pairs thus passing through an angle at the axis of more than 90°.

45 As the construction of the device has thus been described in detail, brief reference is now had to its use and modus operandi: This propeller may be manufactured as a left-turn propeller or a right-turn propeller, as desired. In either case, rotation of the propeller with the propeller shaft on which it is mounted, will result in forcing the 50 boat forwardly when the propeller is rotated in one direction and reversing the movement of the boat when the rotation of the propeller is reversed. Thus, when it is desired to stop forward movement of the boat, rotation of the propeller 55

shaft and operation of the propeller is discontinued and if required, the shaft or propeller may be reversed to quickly bring the boat to a standstill or reverse movement of the boat, in the water.

5 From the foregoing description taken in connection with the accompanying drawing, it will be manifest that a propeller is provided that will fulfill all the necessary requirements of such a device but as many changes could be made in the 10 above description and many apparently widely different embodiments of my invention may be constructed within the scope of the appended claims, without departing from the spirit or scope thereof, it is intended that all matters contained 15 in the said accompanying specification and drawing, shall be interpreted as illustrative and not in a limitative or restrictive sense.

Having thus described my invention, what I claim as new and desire to secure by Letters 20 Patent is:

1. A propeller including an elongated propeller sleeve adapted to be keyed on a propeller shaft; forward and rear pairs of propeller blades arranged to extend respectively from said sleeve at 25 right angles to one another and in overlapping relation; each of said blades being constructed of thin material with flat forward and rear faces; each blade being increased in width from its inner end attached to the propeller sleeve adjacent one 30 end of the latter, to the outer wide and spaced

free end of the blade; each pair of blades, together with the intermediate portion of the sleeve in end elevation substantially describing an S; said blades being thrust rearwardly from their inner ends to their outer ends.

2. A propeller including an elongated propeller sleeve adapted to be keyed on a propeller shaft; a pair of forward blades of substantially arcuate form extending radially from diametrically opposite portions of said sleeve adjacent the forward 10 end thereof; the blades of said forward pair increasing in width as they extend outwardly from said sleeve, being oppositely turned and describing each an arc of approximately 180°; a corresponding pair of rear blades of like design extended 15 radially from diametrically opposite portions of said sleeve adjacent the rear end thereof and from points at right angles to the points of attachment of said first mentioned pair of blades; each pair of said blades together with the intermediate portion of the sleeve in end elevation substantially 20 describing an S and said blades individually passing through an angle of more than 90° at the axis overlap so that in end elevation a continuous unbroken propeller surface or area is 25 provided, said blades being constructed of thin material and having flat forward and rear faces always in a plane at right angles to the axis of said sleeve.

ABRAHAM EDISON GREENE. 30
